[57] CLAIM

The ornamental design for a side draining dish rack, as shown and described.

DESCRIPTION

FIG. 1 is a front perspective view of a side draining dish rack embodying my new design.

FIG. 2 is an enlarged top plan view thereof.

FIG. 3 is a front elevational view thereof.

FIG. 4 is a rear elevational view thereof.

FIG. 5 is a bottom plan view thereof.

FIG. 6 is an end elevational view thereof.

FIG. 7 is a cross-sectional view on line 7—7 of FIG. 2.

FIG. 8 is a cross-sectional view on line 8—8 of FIG. 2.

FIG. 9 is a longitudinal sectional view on line 9—9 of FIG. 2.

The end opposite to that shown in FIG. 6 is a mirror image thereof.
